BUILDING REINFORCEMENT

Edward G. Lamel, Los Angeles, Calif.

Application December 13, 1933, Serial No. 702,180

5 Claims. (Cl. 72—116)

This invention relates to devices used in building structures, and more particularly for reinforcements in plaster or associated with plaster.

One of the objects of this invention is to puncture the reinforcement so as to form burrs of approximately even depth to facilitate an even spreading of plaster.

Another object is to provide a reinforcement that will lend itself to bending in corners and still have a desired stiffness.

Another object is to provide a reinforcement designed with engagements along the edges for interengaging adjoining reinforcements.

It is still another object of this invention to provide a reinforcement sheet, which has sufficient rigidity and mechanical strength to hold its shape during and after construction with a minimum of additional supporting structure.

It is still another object of this invention to provide a reinforcement sheet, which can withstand applied loads with a minimum of deformation.

Other objects will appear from the following description and appended claims as well as from the accompanying drawing, in which—

Fig. 1 is a fragmentary front elevation of reinforcements designed according to this invention.

Fig. 2 is a cross section of one of the burred portions on line 2—2 of Fig. 1.

Fig. 3 is a cross section of a slightly modified form of burred portion.

Fig. 4 is a cross section through the interengagement between adjoining reinforcements.

From the illustration in Fig. 1 it should be clear that the burrs are intended to be as close as possible in order to give a desired stiffness to the reinforcement or lath. However, the spacing is also intended to be so that the reinforcement may be bent according to curves at corners of adjoining walls, nevertheless to be rigid enough to retain its form while plaster is applied to the lath or reinforcement.

The individual burrs of, either, the type illustrated in Fig. 2, or the type illustrated in Fig. 3, are readily made of even or equal depth or height, so as to facilitate an even application of mortar or plaster.

In the form illustrated in Fig. 2, as the reinforcement 5 is punched at 6, the metal is forced outwardly and crimped with the edge 7 folded upon the main body of the reinforcement. A reinforcement sheet is thus formed, in which the 55 walls forming the tubular apertures have flared

edges, which form a raised surface of substantially uniform height.

A slightly different procedure is followed in the form illustrated in Fig. 3, the reinforcement 5 being depressed at 8, but the edge 9 being crimped inwardly instead of outwardly. In both of the forms illustrated by Figures 2 and 3, the edges 7 and 9 respectively provide a large surface for the adhesion and locking of the plastic material during application. These edges 10 also serve to bind the applied material to the reinforcement sheet during the life of the structure. Thus, even though the material be badly cracked, as during an earthquake, it will not break loose from the reinforcement in large 15 masses; but will cling to the edges.

Reinforcements of this type are generally furnished to the trade in certain sizes as to length and width.

Commonly, however, there remains a space 20 between adjoining reinforcements, to be covered by plaster.

In the present case, each individual reinforcement is provided with engaging edges on all sides whereby adjoining reinforcements can be firmly 25 interengaged, in Fig. 1 such engaging edges being indicated at 10, while the cross sectional view in Fig. 4 shows a rider 11 engaged over two adjoining engaging edges.

With this improvement, a cracking between 30 reinforcements or so-called metal-lath sections is very much reduced, so that plaster in general in walls as well as in corners will retain its original finish much better.

Provided with a suitable thickness and 35 strength of plastering material, a structure will stand up even regardless of the condition of other parts of a structure, such as studdings and beams.

While, with the evenly shaped burrs, individual layers of plastering material may be applied rather evenly by even an unskilled person, the rider 11 between each pair of adjoining pieces of the several lath-sections in a wall serves to form a guide for the plasterer in the 45 finished job, and it must be understood that such riders can be made according to the requirements of contractors as to different thicknesses of plastering or concrete finish over a skeleton structure.

Having thus described my invention, I claim:—

1. A structure reinforcement sheet having a plurality of tubular members projecting therefrom, the walls of said tubular members having 55

flared edges for engaging the reenforced material, and the bases of said tubular members having a flared portion joining the main body of the sheet.

5. 2. A structure reenforcement sheet having a plurality of tubular members projecting in one direction therefrom, the walls of said tubular members having flared edges forming a raised surface of substantially uniform height, and the other side of said sheet having a substantially smooth surface.

3. In a structure reenforcement, a sheet having a plurality of tubular members projecting therefrom, the walls of said tubular members 15 providing a raised surface for engaging the reenforced material, the edges of said sheet being folded to form an engaging means, and a con-

necting member slidably engaging over said engaging means for connecting adjoining sheets.

4. A structure reenforcement sheet having a plurality of tubular members projecting therefrom, the walls of said tubular members forming a raised surface of substantially uniform height, said tubular members having flared bases joining the main body of the sheet. 5

5. A structure reenforcement sheet having a plurality of tubular members projecting therefrom, the walls of said tubular members forming a surface raised above the main body of the sheet, and the edges of the walls of said tubular members, being curved back toward the main body of the sheet. 10

15 EDWARD G. LAMEL.
